STATIC DRY MECHANISM FOR A CLOTHES DRYER

Leo V. Buck, Effingham, Ill., assignor to Borg-Warner Corporation, Chicago, Ill., a corporation of Illinois

Application December 27, 1954, Serial No. 477,825

3 Claims. (Cl. 34—91)

This invention relates, in general, to laundry apparatus, and has particular reference to a mechanical control means manually operable by the user for selectively stopping the rotation of the clothes dryer cylinder in order to afford drying of fabrics by maintaining the cylinder stationary or tumbling the fabrics by permitting the cylinder to revolve.

Otherwise stated, the instant invention is concerned with a mechanical control means for a clothes dryer cylinder adapted for advantageous incorporation in a domestic or household dryer of the character completely disclosed in my copending patent application, Serial No. 424,318, filed April 20, 1954, and entitled "Automatic Drying Apparatus," and which is designed for effective operation in drying of even the daintiest fabrics.

It is well known that certain fabrics are not conducive to tumbling in the conventional revolving cylinder type dryer. Moreover, certain fabrics cannot withstand the high temperatures normally employed in conventional dryers of this general class. Furthermore, in order to facilitate the drying of fabrics and particularly fabrics which have been washed by a conventional washing machine or by hand, it is desirable not only to remove the surplus water from the fabrics, but it is also desirable to further dry the clothes by circulating air thereover and therethrough, where the air so circulated may be warmed by a heater or may be of room temperature.

Accordingly, an important object and accomplishment of the present invention is to provide means including a selector whereby the user may, at his election pass heated air or air of room temperature through the dryer.

A further important object and accomplishment of the invention is to provide a clothes dryer of the type hereinbefore described and having incorporated therein means whereby the user may selectively rotate the drum to tumble the clothes or cause said drum to be held stationary to effect a so-called "static drying," with a further choice of passing heated air on through the cylinder.

In connection with the above, another important object and accomplishment of the invention is to provide a dryer having incorporated therein conveniently accessible means, whereby the user may selectively cause the drum to rotate or hold the drum stationary.

In one of its aspects, the present invention contemplates a clothes dryer having incorporated therein air moving means directly associated with the rotatable drum, the air moving means comprising a relatively large fan assembly driven by the same driving mechanism which drives the drum and operable to cause the passage of an unusually large amount of air through the drum for effectively "wiping" the clothes contained therein thus efficiently removing moisture from the clothes.

Heretofore, dryers of the type contemplated by this invention employed relatively high temperatures with a relatively small amount of air flow to effect drying of fabrics contained in the dryer. These relatively high temperatures provided not only dangers of fire during their

2

operation but damage to dainty fabrics and possible burning of the hands of the user during certain operations of the dryer.

In order to effectively eliminate aforesaid dangers, 5 this invention contemplates a dryer having relatively low operating temperatures ranging from 110 degrees to 140 degrees, and further contemplates the provision of means to cause passage of a relatively large volume of air through the cylinder under pressure and constantly away from the heating means whereby to eliminate hazards and dangers of firing of the fabrics contained in the drum.

Additional objects, features and advantages of the invention disclosed herein will be apparent to persons skilled in the art after the construction and operation are 10 understood from the within description.

It is preferred to accomplish the various objects of this invention and to practice the same in substantially the manner as hereinafter more fully described, and as 15 more particularly pointed out in the appended claims.

20 Embodiments of the invention are illustrated in the accompanying drawings forming a part hereof and wherein:

Fig. 1 is a front elevational view of a clothes dryer embodying features of the present invention with the front door panel removed and certain other parts thereof broken away to show the arrangement and disposition of a drum lock with which the present invention is concerned;

25 Fig. 2 is a sectional view of Fig. 1 taken along the plane of the line 2—2 thereof;

Fig. 3 is a fragmentary elevational view, somewhat enlarged, of the upper lefthand portion of Fig. 2 showing in detail the drum lock contemplated by the present invention;

30 Fig. 4 is a vertical sectional view of Fig. 3 taken in the plane of the line 4—4 thereof; and

Fig. 5 is a view similar to Fig. 4 showing the drum lock in the operated position.

35 The drawings are to be understood to be more or less of a schematic character for the purpose of illustrating and disclosing a typical or preferred form of the improvements contemplated herein, and in the drawings like reference characters identify the same parts in the 40 several views.

In the exemplary embodiment of the invention depicted in Figs. 1, 2, 3, 4 and 5, the dryer contemplated by this invention comprises, in general, the component assemblies shown and described in said copending application, and are referenced herein by letters as follows: 45 a cabinet A as shown in Fig. 1; a clothes drum disposed within the cabinet A and rotatable on a substantially horizontal axis and effective to tumble the fabrics disposed therein, the drum B being mounted for pivotal movement by means of a universal joint 9, said joint being fully disclosed in Fig. 7 of said copending application; 50 an air moving fan assembly C axially disposed with respect to the drum B and effective to cause a relatively large volume of air to pass through said drum B for contact with the fabrics disposed therein for absorption of moisture whereupon said moisture is conveyed outwardly and away from the machine with said air; a driving mechanism D effective to cause rotation of said drum B and said air moving fan assembly C; a static dry control E 55 associated with said drum B and effective to control rotation or nonrotation of said drum responsive to manual operation of said static dry control means by the user as desired; an air heating assembly F over and through which ambient air is drawn by said air moving fan assembly C effective to raise the temperature of said ambient air before entry thereof into said drum B whereby said air will be more effective to absorb moisture in the fabrics 60 65 70

contained in said drum B; a lint trap assembly G effective to filter out lint contained in the air passing from said clothes drum before it is discharged from the dryer to provide substantially lint-free air at the discharge openings; air discharge ports H providing a vent system; and a timer mechanism J adapted to regulate the operation of the dryer with respect to a selected drying time and permitting selection by the user of drying by room temperature air or by heated air.

Referring now to Figs. 1 and 2 there is shown a drying apparatus of substantially the same construction and design as that disclosed in said copending application. As is apparent in Fig. 1 a drum B is supported for rotation upon an idler pulley 10 as well as driven pulley 11. These pulleys engage a tire 12 secured to the outer periphery of the drum B as is more readily apparent in Fig. 2.

Since the present invention is not concerned with the precise construction and arrangement of the various components of the drying device, it is not deemed necessary to describe them in great detail. Accordingly, only those portions of the drying device which are adjacent to and cooperate with a drum lock, indicated generally by the reference numeral E, will be described in detail. It is to be understood that the details of construction of an automatic dryer and/or its associated parts may be modified to suit any particular conditions or method of manufacture and it is not contemplated that the present invention be limited to the construction and arrangement of elements shown except where such construction and arrangement deals specifically with the invention disclosed herein.

Generally the present invention relates to a lever device mounted on the front panel of the dryer immediately inside the panel door for locking the drum B in a stationary position. Operation of the drum locking device will cause the forward end of the drum (left side as viewed in Fig. 2) to be lifted off driving pulley D thus holding the drum stationary.

Having thus described by way of example a possible adaptation of the mechanical stop means for a clothes dryer drum and having described the general environment surrounding the adaptation, the specific construction and function of the parts of said locking device when mounted in an automatic clothes dryer will now be described in detail. Referring now to Fig. 1 and Fig. 2 there is shown a circular segmental bracket member 13 having a U-shaped cross-section secured to the front panel of the clothes dryer by means of screws 14. Among other functions the bracket 13 serves as a mounting for an incandescent lamp indicated at 16 for lighting the interior of the drum. Disposed between the bracket 13 and a flange 17 (Fig. 3) formed integral with a front panel 18 of the dryer cabinet is an annular gasket indicated by the reference numeral 19. As is more apparent in Fig. 3 the annular gasket 19 acts to make a tight seal between the panel 18 of the dryer and the door panel 21. As shown and described in said copending application an annular felt seal 22 is disposed around the upper side of the flange 17 and is formed with a slot 23 (Figs. 4 and 5) for receiving flange member 24 formed on the rotatable drum B. Secured to the under side of the flange 17 by means of a sheet metal screw 26 is a U-shaped spring clip 27. An arm 25 integral with the spring clip 27 passes through a slot in the flange 17 and acts to maintain the position of the clip 27.

Referring now to Fig. 4 there is shown a crank 28 held within the leaves of the spring clip 27 by the engagement of a pimple 29 therewith.

A depending leg 30 of the crank 28 projects through an elongated slot 31 formed in the bracket 13 while a head 32 projects through a slot 33 formed in the flange 17. In Figs. 3, 4, and 5 it is apparent that a felt seal 22 is formed with a cutout portion 34 to allow free movement of the head 32 and to permit the head 32 to engage the under side of the flange 24 in a manner and

for a purpose to be described hereinafter. The gasket 19 has a similarly cut out portion as at 36 to provide clearance for the spring clip 27 and the crank 28.

Surrounding the slot 33 and suitably tack welded to the flange 17 is an apertured plate 37. The plate 37 acts as a bearing surface for a laterally extending ear 38 formed integral with the head 32 when the ear is in the position shown in Fig. 5. Suitably secured to the upper side of the ear 38 is a shoe 39. The shoe 39 may be molded of plastic material such as compounds of nylon, polyethylene and polyvinylchloride and may be of laminated or other reinforced structure. Connected to the leg 30 of the crank 28 is a handle 41. The handle 41 and the leg 30 are relatively movable but are held in tight frictional engagement by the bolt 42 and the nut 43. A dog 44 formed on the handle 41 and engageable with the leg 30 at two points 46 and 47 thereon limits the relative motion between the handle and the leg to the extremes denoted by the solid line position of the handle 41 and the dotted line position thereof shown in Figs. 4 and 5.

The operation of the drum locking device will now be described. In Fig. 4 the locking device is shown in the unoperated position. The handle 41 is held in place parallel to the bottom of the bracket 13 by the friction existing between the handle and the leg 30. The crank 28 is held in the position shown by the engagement of the pimple 29 with the spring clip 27 so that the head 32 is clear of the drum flange 24. Rotation of the handle 41 to the right (Fig. 4) will cause the crank 28 to be withdrawn from the spring clip 27 and as this occurs, the ear 38 will ride up on and make pivoting contact with the plate 37. Continued rotation of the handle 41 to the right will cause the heel 48 of the shoe 39 to engage the under side of the flange 24. When the handle 41 is rotated to the position shown in Fig. 5, the drum locking device has been fully operated and the shoe 39 by virtue of its engagement with the flange 24 will have raised the forward end of the drum B clear of the driving pulley D (Fig. 1), the universal joint 9 permitting the forward end of the drum to be raised off of the driving pulley. Since the flange 24 is received within the slot 23 formed in the felt gasket 22, the gasket 22 will be raised slightly or ride with the flange 24 as is apparent in Fig. 5. While the drum B is held in the raised position and out of engagement with the drive pulley D, the drum will remain stationary. Furthermore, it is to be particularly noted that while the drum is held stationary, the drive pulley D and the fan C may be rotated by the dryer drive mechanism without disturbing the stationary attitude of the drum.

After operating the drum locking device the handle 41 may be further rotated to the right as viewed in Fig. 5 until the handle assumes the dotted line position shown therein. In this manner the handle may be rotated clear of the opening to the dryer, thus eliminating any obstruction in the opening.

It is anticipated that the arm 41 may be formed of metal or plastic material and that it be so designed that when it is in the unoperated position (Fig. 4) the handle will intimately contact or be partially recessed in the bracket 13 and when in the operated position (Fig. 5) the handle will intimately contact the annular gasket 19 so as not to obstruct the introduction or withdrawal of laundry in either position.

Consequently, it is to be noted that by virtue of the provision of relative motion between the handle 41 and the crank 28 a means has been provided for casting the handle 41 to a relatively obscure position after the drum locking device has been placed either in its operated or unoperated position.

From the foregoing specification and drawings it is apparent that an improved drum locking device has been disclosed which is advantageous for the following reasons:

(1) The device is readily operable upon opening the door leading to the interior of the drying device.

(2) The structure of the elements thereof are simple in design and lend themselves readily to mass production methods.

Having thus disclosed and described a preferred embodiment of my invention, it is anticipated that many modifications may be made therein without departing from the spirit and scope of the invention.

I claim:

1. In a laundry apparatus having a rotatable cylindrical basket pivotally mounted within a casing and including a driving pulley for engaging and rotating said basket, said casing having means defining an access opening in one end wall thereof through which articles may be disposed into said basket, said basket having means defining an access opening in one end thereof, one of said means overlying the other of said means, a lever mounted upon the casing adjacent said access openings and operable to engage both said means and pivot said basket to disengage said basket from said driving pulley.

2. In a laundry apparatus having a rotatable cylindrical basket pivotally mounted within a casing and including a driving pulley for engaging and rotating said basket, said casing having means defining an access opening in one end wall thereof through which articles may be dis-

posed into said basket, said basket having means defining an access opening in one end thereof, one of said means being adjacent the other of said means, a lever mounted upon the casing adjacent said access openings and operable to engage both said means and pivot said basket to disengage said basket from said driving pulley.

3. In a laundry apparatus having a basket rotatable about an axis and pivotally mounted within a casing and including a driving pulley for engaging and rotating said basket, said casing having an access opening in one end thereof defined by a flange, said basket also having an access opening in one end thereof defined by a flange, said last named flange overlying said first named flange and being radially spaced therefrom, lever means in engagement with both said flanges and adapted to move said basket away from said casing flange and away from said driving pulley whereby said basket is disengaged from said driving pulley.
